UNITED STATES PATENT OFFICE.

JOHN H. KULOW, OF BUFFALO, NEW YORK.

DESIGN FOR A PENHOLDER.

47,794.

Specification for Design.

Patented Sept. 7, 1915.

Application filed October 21, 1914. Serial No. 867,914. Term of patent 3½ years.

To all whom it may concern:

Be it known that I, JOHN H. KULOW, a citizen of the United States, and resident of Buffalo, in the county of Erie and State of New York, have invented a new, original, and ornamental Design for Penholders, of which the following is a specification, reference being had to the accompanying drawing, forming a part thereof.

The figure is a perspective view of a pen holder illustrating my new design.

What I claim is:

The ornamental design for a pen holder substantially as shown.

JOHN H. KULOW.

Witnesses:

OSWALD H. SCHILLER,

ALBERT E. DIETERICH.
